(57) **CLAIM**

The ornamental design for a Wifi borescope inspection camera, as shown and described.

DESCRIPTION

FIG. 1 is a perspective view of the Wifi borescope inspection camera showing my new design;

FIG. 2 is a front view of the Wifi borescope inspection camera;

FIG. 3 is a rear view of the Wifi borescope inspection camera;

FIG. 4 is a left view of the Wifi borescope inspection camera;

FIG. 5 is a right view of the Wifi borescope inspection camera;

FIG. 6 is a top view of the Wifi borescope inspection camera;

FIG. 7 is a bottom view of the Wifi borescope inspection camera; and,

FIG. 8 is a perspective view illustrating the Wifi borescope inspection camera in an open status.

The surface(s) or poration(s) of the article shown in broken lines in the drawings being for illustrative purpose only and forming no part of the claimed design.
